SMOKING PIPE

Arthur R. Perkins, Farmington, Mo.

Application June 8, 1938, Serial No. 212,530

1 Claim. (Cl. 131—213)

This invention relates to smoking pipes.

The object of the invention is to provide a tobacco pipe with a moisture chamber between the bowl of the pipe and the mouth piece and separated from direct communication with the tobacco, or combustion chamber of the pipe bowl.

A further object of the invention is the provision of a smoking pipe embodying the above features in which the moisture and nicotine enters the moisture chamber at the mouth piece end of the moisture chamber only.

A further object of the invention resides in the forming of a smoke passage by the connecting of a longitudinal stem groove, a transverse stem passage and a longitudinal stem and mouth piece passage.

A still further object of the invention resides in the provision of a pipe which can be readily cleaned of foreign substance, provide a cool smoke, a perfect draft, compact and simple in structure and comparatively inexpensive in the cost of manufacture.

With the above and other objects in view, as will be apparent hereinafter, the invention consists in the novel features of construction, arrangement and combination of parts, hereinafter more fully described and finally pointed out in the claim hereto appended.

Referring to the accompanying drawing, wherein like characters of reference denote similar parts throughout the several views:

Fig. 1 is a longitudinal sectional view of a tobacco pipe embodying the features of my invention.

Fig. 2 is a longitudinal sectional view of the pipe bowl and bowl stem.

Fig. 3 is a longitudinal sectional view of the mouth piece, or bite and its cylindrical projecting stem.

Fig. 4 is a view looking in the direction of the arrow in Fig. 2.

Fig. 5 is a top plan view of the mouth piece and its projecting stem.

Fig. 6 is an enlarged sectional view of the mouth piece stem taken on line 6—6 of Fig. 5.

Fig. 7 is an enlarged sectional view of the mouth piece stem taken on line 7—7 of Fig. 5.

Briefly, in carrying out the invention, I provide a smoking pipe with a stem having separable parts, including a plurality of smoke passages and a moisture and nicotine chamber out of direct communication with the combustion chamber of the pipe bowl.

In the drawing, there is shown a suitable bowl 1, having a combustion chamber 2 in which to

bacco is adapted to be placed for smoking. The bowl 1 is provided with a bowl stem part 3 formed integral therewith and having a longitudinal bore 4 inwardly from the free end thereof and stopping at its inner end short of the combustion chamber 2 to form a solid wall 5. The wall material 5 between the combustion chamber 2 and the bore 4 is provided with a smoke inlet passage 6. The smoke inlet passage 6 is out of axial alignment with the bore 4 and to the upper side 10 thereof. The smoke inlet passage 6 communicates at one end with the side wall of the combustion chamber near the bottom thereof, and, at its opposite end with the face of the solid wall 5, as clearly shown in Fig. 2. 15

I also employ a suitable mouth piece part 7 provided with a bite 8 and having a bore or smoke outlet passage 9. The mouth piece 7 includes a cylindrical stem 10 projecting from one end thereof and is provided with a relatively 20 short smoke outlet passage 11, which passage 11 is a continuation of the mouth piece smoke passage 9.

The cylindrical mouth piece stem 10 is adapted to be fitted snugly into the bore 4 of the bowl 25 stem part 3 to form a tight joint therebetween. The mouth piece stem 10 serves as means for disconnectively connecting the mouth piece 7 with the bowl stem part 3 to close the bore 4 from communication with the combustion chamber 2, 30 as clearly shown in Fig. 1.

The cylindrical mouth piece stem 10 is provided on its upper side with a longitudinal groove 10', as shown in Figs. 3, 5 and 6, and when fitted in the bore 4 forms a smoke inlet channel 12, 35 which channel communicates directly with the smoke inlet passage 6 when the bowl stem part and the mouth piece part are fitted, or joined together through the medium of the stem 10, as shown in Fig. 1. The groove 10' starts at the free end of the stem 10 and stops short of the juncture of the stem 10 with the mouth piece 7, 40 as shown in Figs. 3 and 5. The stem 10 being less in outside diameter than the mouth piece 7, and when the separable pipe stem parts are fitted, 45 or joined together, the end face 13 of the bowl stem 3 will tightly engage the mouth piece shoulder 14, and, the flat end face 15 of the stem 10 will tightly engage the end face 16 of the bowl stem wall 5 to form a perfect joint between the stem 10 and bowl stem part 5.

The lower half of the mouth piece stem 10, as clearly shown in Fig. 3, is provided with an elongated cutaway portion, or recess intermediate the ends thereof, providing thereby a flat ceiling sur- 55

face 17, and the inclined end walls 18 and 19. The free end portion of the stem 10 provides a head adjacent the inclined wall 18 so that the edge of the wall 18 forms a scraping edge 20, as clearly shown in Fig. 7.

A suitable transverse smoke, moisture and nicotine inlet passage 21 is formed in the mouth piece stem 10 and it connects the mouth piece end of the stem groove 10' with the like end of the elongated recess formed on the lower half of the stem 10. When the stem 10 is positioned in the bore 4 of the bowl stem part 3, the inlet passage 21 is disposed vertically relative to the stem groove 10' and the stem recess therebelow so that the lower end of the inlet passage 21 serves as a fluid, moisture and nicotine outlet. The axial stem passage 11, which is a continuation of the mouth piece smoke passage 9, terminating with one side of the vertical inlet passage 21, permits only pure smoke to pass into the stem passage 11 and then into and out of the mouth piece passage 9 to provide for a clean, cool smoke.

When the mouth piece stem 10 is fitted into the bore of the bowl stem part 3, the cutaway portion, or recess on the lower side of the mouth piece stem 10 provides a fluid or moisture and nicotine chamber 22 between the walls 17, 18 and 19 of the mouth piece stem 10 and the wall of the bore 4 in the bowl stem 3, as clearly shown in Fig. 1 so that when smoking the pipe, fluid, such as moisture and nicotine will flow downwardly through the vertical passage 21 directly into the nicotine chamber 22, which leads back toward the combustion chamber of the pipe bowl below the smoke groove 10' and not directly connected with the combustion chamber of the pipe bowl.

It will be observed from Fig. 1 of the drawing, that when the pipe bowl stem part and the mouth piece stem part are assembled, that the stem channel 12 is in alignment and in direct communication with the smoke inlet passage 6 so that smoke will travel through irregular path, or course to the smoke passage in the mouth piece, and, that the heavy liquid substance such as moisture and nicotine will be deposited in the chamber 22 below and behind the vertical passage 21 so that it cannot be drawn through the mouth piece passage, and, in no instance can smoke

pass directly from the pipe bowl through the nicotine receiving chamber 22 to the mouth piece passage, thereby providing a clean, cool smoke.

Also, it will be observed it is easy to clean the smoke groove 11 on the stem 10 when the stem is removed from the bowl stem bore 4, by wiping the same out, and, the vertical passage 21, as well as the smoke passages 9, 11 and 21 can be readily cleaned with a pipe cleaner, or the like. The bowl stem passage 6 can also be readily cleaned when the mouth piece stem 10 is disconnected from the bowl stem part 3.

The many advantages of the herein described invention will readily suggest themselves to those skilled in the art to which it appertains.

From the foregoing description, it is evident that a simple device for this purpose has been disclosed, but it is to be understood that I have illustrated and described a preferred embodiment only of the invention and do not desire to restrict, or limit myself to the very details of the construction shown and described, which is merely illustrative, it being obvious that changes, not involving the exercise of invention, may be made without conflicting or departing from the spirit of the invention within the scope of the appended claim.

What I claim is:

In a smoking pipe, the combination with a bowl having a tubular neck and a mouth piece having a smoke passage, of a solid stem projecting from the mouth piece and receivable within said neck, said stem being cylindrical at opposite ends and semi-cylindrical intermediate said ends with the plane surface of the semi-cylindrical intermediate portion adapted to be spaced from the bottom surface of the inner wall of the bowl neck to provide a nicotine chamber below the stem portion only, said bowl having a bowl passage and said stem having a vertical passage communicating at its lower end with the forward end of the nicotine chamber and communicating intermediate its ends with the mouthpiece smoke passage, the upper curved face of the stem being provided with a longitudinal smoke groove communicating at one end and in axial alignment with said bowl passage and communicating at its opposite end with the upper end of said vertical passage.

ARTHUR R. PERKINS.
